UNITED STATES PATENT OFFICE.

CHARLES RYSTROM, OF ROCKFORD, ILLINOIS.

LOCK-NUT.

No. 856,728.

Specification of Letters Patent.

Patented June 11, 1907.

Application filed December 18, 1905. Serial No. 292,233.

To all whom it may concern:

Be it known that I, CHARLES RYSTROM, a citizen of the United States, residing at Rockford, in the county of Winnebago and State 5 of Illinois, have invented certain new and useful Improvements in Lock-Nuts, of which the following is a specification.

The object of this invention is to construct a lock nut having its threaded opening inclining laterally to its lengthwise direction when separated from the bolt, and when placed in connection with the bolt its threaded opening will be formed to conform to the bolt, thereby causing an impinging effect upon the 15 bolt, sufficient to hold it from accidental displacement.

The further object of this invention is to construct a lock nut of a series of coils provided with a central screw-threaded opening 20 and having the face of one coil seated into the adjacent face of the nut coil, in order that when a wrench is applied to the nut, the coils will be held from separating or twisting past one another.

25 In the accompanying drawings, Figure 1 is a plan view of my improved lock nut. Fig. 2 is an elevation. Fig. 3 is a vertical central section. Fig. 4 is an elevation of the nut applied to a bolt. Fig. 5 is a vertical section of 30 the nut in its connection with a bolt. Fig. 6 is an elevation of the nut showing the connected coils.

The lock nut is composed of a single strip or bar of material fashioned into a series of 35 inter-engaging coils, as 1, 2, 3 and 4 having preferably hexagonal exterior contour, provided with a central screw-threaded opening 5 to receive a bolt or the like. After the formation of this screw-threaded opening 5 the 40 successive coils of which the nut is composed

are displaced laterally, progressively, that is to say, for example, the coil 3 is shifted laterally with respect to the coil 4; the coil 2 laterally with respect to coil 3, and the coil 1 laterally with respect to coil 2, as clearly 45 shown in Fig. 3; whereby the screw-threaded opening of the nut runs obliquely to the line of the bolt or other device to which the nut is to be applied.

In placing the nut in connection with a 50 bolt 6 it is turned on in the usual manner which will cause the coils to assume the position they occupy before being shifted laterally, and as the coils are of spring material, they will impinge against the bolt and hold 55 the nut against accidental displacement.

In the manufacture of the nuts the meeting faces of one coil are embedded into seats in the meeting face of the adjacent coil as shown at 7 Figs. 2 and 4 so that in turning the 60 nut in connection with the bolt, one coil will exert its influence on the coil next to it, thereby forming practically a solid nut.

I claim as my invention—

1. A lock nut consisting of a bar of mate- 65 rial fashioned into a series of screw-threaded coils shifted progressively laterally to provide an oblique screw-threaded opening.

2. A lock nut consisting of a bar of mate- 70 rial fashioned into a series of screw-threaded coils shifted progressively laterally to provide an oblique screw-threaded opening, and the meeting faces of the several coils being embedded in seats in the faces of the adjac- ent coil.

CHARLES RYSTROM.
